(57) **CLAIM**

What is claimed is the ornamental design for an wine bottle rack, as shown and described.

DESCRIPTION

FIG. 1 is a perspective view of an wine bottle rack showing a new design;

FIG. 2 is a front view of the wine bottle rack of FIG. 1;

FIG. 3 is a rear view of the wine bottle rack of FIG. 1;

FIG. 4 is a side view of the wine bottle rack of FIG. 1;

FIG. 5 is a top view of the wine bottle rack of FIG. 1; and,

FIG. 6 is a bottom view of the wine bottle rack of FIG. 1.
The broken lines are for illustrative purposes only and form no part of the claimed design.
